UNITED STATES PATENT OFFICE.

CYRUS CHAMBERS, JR., OF PHILADELPHIA, PENNSYLVANIA.

MACHINE FOR FOLDING TOWELS, NAPKINS, &c.

SPECIFICATION forming part of Letters Patent No. 297,673, dated April 29, 1884.

Application filed March 31, 1883. (No model.)

To all whom it may concern:

Be it known that I, CYRUS CHAMBERS, Jr., a citizen of the United States, residing at the city and county of Philadelphia, and State of Pennsylvania, have invented certain new and useful Improvements in Machines for Folding Towels, Napkins, and Similar Articles, of which the following is a full, clear, and exact description, reference being had to the accompanying drawings.

Figure 1, Sheet 1, is a plan or top view of my machine with the feed-table and conveying-tapes removed. Fig. 2, Sheet 2, is a transverse section of the invention on the line *a b*, Fig. 1, with the feed-table in place. Fig. 3 is a detail plan, enlarged, of one of the rotary brushes with its connections and adjustments. Fig. 4 is a longitudinal vertical section on the line *c d*, Fig. 2, enlarged, the brush-wheel being broken off through the vertical middle thereof. Fig. 5 is an end elevation of one of the boxes in which the first pair of folding-rolls and brush-shafts are journaled, as herein-after described.

Like letters of reference, where they occur in the several figures, mark corresponding or similar parts.

The purpose of this invention is to provide a power-machine for smoothing out and folding articles from the laundry—such as towels, napkins, &c.—with convenience and dispatch.

I term the machine a “laundry-folder.”

Referring to the annexed drawings, A is a horizontal feed-table, upon which the articles to be folded are laid, one at a time, by the operative, to a gage lengthwise over a longitudinal slot, S, in the table, so that the middle of the article will be in line with said slot. In this position it is struck through the latter into the bite of the first pair of folding-rolls, 1 2, beneath the table, by means of a blade, K, vibrating at regular intervals through the action of a cam, P, upon the cam-shaft K⁵, in the ordinary manner with folding-machines.

On its way to this pair of rolls the ends of the article are brought into contact, respectively, with a pair of rapidly-revolving circular brush-wheels, B, placed horizontally beneath the feed-table, and whose points of contact are in the vertical plane with those of the first pair of rolls, 1 2. These brushes separate and smooth out the end fringes of the towel, &c.,

should the article be provided with fringes. The second fold, which is also made lengthwise with the towel, &c., or parallel with the first fold, is given by the second pair of rolls, 2 3, into the bite of which it is struck just as it has about passed through the first pair of rolls, by a blade, K', mounted upon a rock-shaft, c. This blade is caused to vibrate by the operation of a cam, Q, upon the cam-shaft K⁶ and the compression-spring t on rod V connecting the knife-bar with said cam, as seen in Fig. 2. The now twice-folded towel, &c., having passed through rollers 2 3, is carried on upon tapes, (indicated by the dotted lines x, Fig. 2,) which run over the roll 3 and a roller, U, journaled in a bracket, y, secured to the frame of the machine, until it is arrested by a stop, F. Rolls 4 5 are at right angles to 2 3, and opposite the middle of the latter, so that when the article is brought up against stop F, as mentioned, it will be in position to be immediately struck into the bite of rolls 4 and 5, and given a first transverse fold by the third folding-blade, K², Fig. 1, which vibrates at set times, through the action of a cam or eccentric upon the cam-shaft, in the usual manner in folding-machines. The fourth or final fold, which is parallel with the third, is effected by means of the vertical roll-pair 5 6. The relation and function of rolls 4 5 6 correspond with those of the rolls 1 2 3. A fourth folding-blade (not seen in any of the accompanying views) tucks the thrice-folded towel, &c., as it leaves the bite of rolls 4 5 into the bite of rolls 5 6, the location and operation of this blade with reference to rolls 5 6 being as is that of the blade K' to rolls 2 3. As the article passes from between the last folding-rolls, 5 6, it is caught by a fly, O, and laid by it into a packing-trough, T, in the usual manner.

The foregoing is a somewhat general description of the construction and operation of my invention.

I shall now proceed to explain the same in detail.

As the various laundered articles to be folded by the machine differ considerably in thickness, it is desirable to have a provision for the self-adjustment of the folding-rolls to accommodate themselves to the different thicknesses. This is accomplished by journaling

the shafts of one of the rollers of each pair in sliding boxes, which are pressed against by spiral springs *r*. As this is a common expedient for a similar purpose in various machines having coacting rollers, I do not make any claim thereto, and further description of the same will be unnecessary.

The brush-wheels *B*, which smooth out the ends and fringes of the towels, &c., are operated by bevel-gears *C C'*, one of which, *C'*, is on the driving-shaft *H*, (see Fig. 4,) and the other, *C*, on the vertical shaft *d* of the brush-wheel. The boxes or bearings of the brushes, together with the boxes in which the bevel-wheels turn, 15 are carried at the end of a sliding bracket, *D*, that is secured by a bolt, *e*, passing through a slot, *f*, in the bracket upon the top of the journal-boxes, in which the first pair of rollers, 12, and also the shafts *H*, which drive the 20 bevel-wheels, respectively revolve. The latter shafts, *H*, are provided with a spline, *p*, Fig. 4, and the sleeve of the bevel-gear has a corresponding longitudinal groove therein. Thus by slackening up the bolt *e* the brackets *D*, 25 which, as stated, carry the circular brushes and the driving-gears, may be adjusted longitudinally to increase or diminish the distance between the opposite pairs of brush-wheels to suit the lengths of the articles to be passed 30 through the machine. The entire mechanism is driven from a cone-pulley, *M*, on the shaft *m* of roll 5, which, by bevel-gears *K*, turns a shaft, *l*, Fig. 2, which again, by a series of gears, drives the first and second pairs of folding-rolls, the brush-wheels, and the cam-shaft *K'*, from which all the folding-blades are 35 actuated in the usual manner in folding-machines. An eccentric, *N*, on the cam-shaft operates the fly *O*, which packs the folded articles in the trough *T* provided for their reception.

It will be seen by referring to Fig. 2, Sheet 2, that the front part of the frame of the machine extends out beyond the main frame *R* in 45 a manner that renders it convenient for the operator, sitting or standing, to place the articles to be folded in proper position upon the feed-table, and also to reach under the said forward extension of the frame when it may be 50 necessary or desirable to take hold of the towel, &c., after it has gone through or is passing through the first pair of rolls, 12. This is sometimes desirable when, owing to the large size of the article, it is required to cause two 55 or more folds in succession to be given it by the said rolls, instead of but one, as before described. This is done as follows: When the cloth has nearly passed from between these rolls 1 2, the operative seizes hold of the same 60 by extending his or her hand beneath the feed-table, and upon the article being freed from the rolls again places it, as once folded, upon the table *A* in suitable position over the slot therein, and it again receives another fold by

the same rolls, and may then be permitted to 65 pass on between the others of the series of rolls, as hereinbefore described.

The several folding-blades may be timed to operate at suitable intervals, according to the dimensions of the cloth, by adjusting their corresponding cams upon the cam-shaft in the usual manner.

Having thus described my invention, I claim as new and wish to secure by Letters Patent—

1. The combination, with the folding-rolls, 75 of the lateral smoothing-brushes and the vibrating knife for tucking the article to be folded into the bite of said rolls, substantially as and for the purpose stated.

2. The combination of the slotted feed-table, 80 the first pair of folding-rolls, the folding-knife, and the lateral rotary smoothing-brushes, all combined, constructed, and operating substantially as described, and for the purposes specified.

3. The combination, with the slotted feed-table, 85 of the trio of rolls 1 2 3, means, substantially as described, to rotate the same, the first of two said rolls being in a horizontal plane, and the third in a vertical plane with the second of the trio, together with the respective folding-blades for operating the same, and mechanism, substantially as described, to tuck the articles to be folded into the bites of the first and second and of the second and third of the 90 trio of rolls, respectively, substantially as and for the purposes stated.

4. In combination with the slotted feed-table and the folding-rolls and folding-blades, 100 the lateral rotary brushes, and means, substantially as described, for adjusting the same longitudinally, substantially as set forth.

5. The combination, with the first pair of folding-rolls, of the vibrating knife *K*, the rotary smoothing-brushes having the bevel-gear 105 *C*, the feathered shafts *H*, with a bevel-gear, and the adjustable bracket provided with bearings for said gears and brushes, together with mechanism, substantially as shown, for operating said brushes, rolls, and folding-knife, the construction and operation being substantially as and for the purposes set forth.

6. The combination of the slotted feed-table, 115 the lateral brush-wheels, the rolls 1 2 3, and rolls 4 5 6, at right angles to the first-mentioned rolls, together with the respective folding-blades, and the mechanism for operating the same, all combined, constructed, and operating substantially as and for the purposes set forth.

In testimony whereof I have hereunto affixed my signature this 14th day of February, A. D. 1883.

CYRUS CHAMBERS, JR.
